(Continued)

Primary Examiner — T Chase Nelson(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof; and,

FIG. 4 is a rear view thereof.
The broken lines depicting the remainder of the shoe form no part of the claimed design.**1 Claim, 4 Drawing Sheets**| (56)	References Cited
